UNITED STATES PATENT OFFICE

149,404

DESIGN FOR A COMBINATION AUTOMOBILE AND AIRPLANE

Thomas R. Burns, Washington, D. C.

Application May 8, 1946, Serial No. 129,441

Term of patent 14 years

(Cl. D71—1)

To all whom it may concern:

Be it known that I, Thomas R. Burns, a citizen of the United States, residing at Washington, in the District of Columbia, have invented a new, original, and ornamental Design for a Combination Automobile and Airplane, of which the following is a specification, reference being had to the accompanying drawing, forming part thereof.

This application is a continuation-in-part of my copending design application, Serial No. D-119,014, filed April 16, 1945, now abandoned.

Figure 1 is a side elevational view of a combination automobile and airplane, showing my new design,

Figure 2 is a top plan view,

Figure 3 is a front elevational view,

Figure 4 is a perspective view looking upwardly from the front,

Figure 5 is a perspective view looking downwardly from the rear,

Figure 6 is a perspective view of the automobile portion,

Figure 7 is an enlarged front perspective view of the automobile portion, and

Figure 8 is an enlarged rear perspective view of the automobile portion thereof.

I claim:

The ornamental design for a combination automobile and airplane as shown.

THOMAS R. BURNS.
